UNITED STATES PATENT OFFICE

ANDREW STRAND, OF MINNEAPOLIS, MINNESOTA

FLOOR SEPARATOR

Application filed January 11, 1928. Serial No. 245,874.

My invention relates to floor separators which are used in terrazzo surfaced floors to divide the floor into sections and to prevent the same from cracking and breaking in expansion and contraction.

5 My floor separator is designed in a manner to provide an anchoring means of a peculiar nature which is embedded in the concrete floor and the terrazzo surface so that a portion of the same extends flush with the floor and is surfaced off when the terrazzo surface is polished down to the finished form. This leaves the separator showing on the surface of the floor and a feature of my invention is to provide the separator of a 10 design to form an attractive separating means of various designs. I have illustrated in the drawings a particular design which may be termed a wave pattern and obviously other designs may be employed as well as the making of the separating strip straight 15 on that portion which shows along the surface of the terrazzo floor.

It is a feature of the invention to provide 20 a separator having an anchoring means of a design forming a pair of longitudinally extending ribs oppositely disposed on the faces of the separating strip. Between these ribs I provide a straight portion in which a series of openings may be provided. The 25 openings in the portion between the ribs may be for the purpose of receiving anchoring lugs to firmly lock the separating strip embedded in the floor.

30 It is also a feature of my invention to provide a floor separator having the body portion extending comparatively straight and of a flat thin nature, together with an upper edge which is bent in a manner to form different designs, the strip tapering to the straight portion of the same from the edge 35 forming the design.

These features, together with other details 40 of my invention, will be more fully and clearly set forth in the specification and claims.

In the drawings forming part of my specification:

45 Figure 1 is a plan view of a portion of a terrazzo floor showing my separating strip 50 employed therein with a particular design.

Figure 2 is a perspective of a portion of a terrazzo floor and showing a part broken away to more clearly illustrate my separating strip as it would appear embedded in the same.

55 Figure 3 is a plan view of a portion of my separating strip.

Figure 4 is a section on the line 4—4 of Figure 3.

60 In the drawings my separating strip A is formed of strip brass or other suitable material having a comparatively thin nature yet being of sufficient thickness to provide the proper separating means which is adapted to be inserted into a concrete and terrazzo surfaced floor.

65 My separating strip A is formed with a decorative flange B, the upper edge 10 of which is bent in a manner to form a particular design. In the drawings I have illustrated a wave pattern for the upper edge 70 10 of the decorative flange B. Obviously this is only suggestive of a particular pattern and the upper edge 10 may be of any particular pattern or shape so as to provide 75 a decorative separating strip A as is illustrated in the plan view in Figure 1 to separate the concrete floor C which is provided with the upper terrazzo surfaced portion D.

80 The decorative flange B is so shaped as to taper toward the body portion of the separating strip A which extends virtually straight so that the sides 11 of the decorative portion or flange B taper from a straight portion, such as 12, out to the outer edge 10 with a flaring formation. In the wave pattern as is illustrated in the drawings for a convenience in describing my invention shows the side walls 11 tapering outwardly from the straight portion 12 and in waves equally disposed on either side of the straight portion 12. Thus it is evident as 85 illustrated in Figure 3 that the sides 11 taper equally on either side of the center 12 to form the wave pattern to the upper edge 90 10 of the separator A.

95 Directly adjacent the straight portion 12 in the separator A I provide a longitudinally extending reinforcing rib 13 adapted to extend on one side of the surface of the 100

separator A and spaced therefrom I provide a second longitudinally extending reinforcing rib 14 which is separated by the straight portion 15. The portion 14 is disposed to extend to the opposite face to the reinforcing rib 13. This provides a reinforcing rib extending along longitudinally on either side of the body of the spacer A. Below the reinforcing rib 14 I provide a straight flange 14 which constitutes the bottom of the spacer strip such as 16. This provides a spacer with a properly balanced body portion including a flange 16 which extends in line with the interposed straight portion 15 which connects the reinforcing ribs 13 and 14. Then above these portions the decorative flange B projects. This flange B may be of any width to accommodate the thickness of the terrazzo surface 20 of the floor C.

I provide a series of openings 17 within the straight portion 15 of the separator A through which anchoring pins 18 may be placed to more securely anchor the separator 25 in the floor.

When the terrazzo portion D of the floor is polished down to the surface C the decorative edge 10 is polished at the same time and thereby providing a decorative surface 30 in the form of a strip of a particular design extending through the floor to divide the floor into such spaces as is desired. Thus the separator A not only provides a means of separating the concrete and terrazzo surfaced floor in a manner to practically prevent cracking, but to provide such a decorative means of an attractive nature as to make a more desirable separating member in the body of the floor. My separator 35 A also functions in such a manner through the reinforcing members 13 and 14 to provide an expandable means in the width of the separator and to firmly anchor the separator in such a manner as to prevent its 40 bulging out of the terrazzo surfaced floor and to accomplish a result of a very desirable nature.

In accordance with the patent statutes I have described the principles of operation 45 of my separator strip and while I have illustrated and described a particular design and formation thereof I desire to have it understood that this is only suggestive of a means of carrying out my invention and that other forms and shapes may be readily adapted within the scope of the following claims 50 without departing from the spirit of my invention.

I claim:

60 1. A separator for terrazzo surfaced floors including an irregularly edged thin ribbon-like member adapted to form a particular pattern along the length of the spacer, and anchoring members oppositely disposed and 65 extending longitudinally through the body

of said separator for the purposes specified.

2. A floor separator including, a flat strip-like member, longitudinally extending reinforcing anchoring ribs, a straight portion separating said ribs, and a decorative flange having an outer waved edge to provide a decorative line extending to the surface of a terrazzo floor. 70

3. A floor separator comprising, a waved flange adapted to decorate the terrazzo surface thereof with the upper edge of the same, and longitudinally extending anchor means disposed in the body of said separator. 75

4. A floor separator including, a comparatively ribbon-like body portion, reinforcing means extending longitudinally thereof, and a decorative wavy flange adapted to be embedded and surfaced with the terrazzo portion of a floor. 80

5. A floor separator including, a body portion having means for anchoring the same in the floor in a manner to divide the floor into segments to overcome cracking of the same, the separator being embedded vertically into the floor, continuous longitudinally extending anchoring means adapted to project on opposite sides of said separator, and a wavy decorative flange projecting upwardly from the same. 85

6. A floor separator including, a body portion of a thin ribbon-like nature, reinforcing means extending longitudinally through said body portion, and a terrazzo flange adapted to be surfaced with the terrazzo portion of a floor, said flange being waved 100 to form a decorative design when embedded in the floor. 95

7. A separator for concrete bodies including, a flange having an upper edge adapted to form a decorative design, longitudinally disposed reinforcing ribs projecting from either side of said separator, a straight flange portion separating said reinforcing ribs, and a lower straight flange in line with said separating portion. 105

8. A floor separating strip comprising, a decorative flange having the outer edge bent to form a decorative design, the sides of said flange tapering to a straight portion in said strip, and anchoring means disposed in said strip adapted to anchor the same in a floor in a manner to divide the floor. 115

9. A floor separator adapted to be embedded in the body of the floor to extend vertically therein, an upper decorative flange portion having the outer edge adapted to be surfaced with the floor and bent to form a particular design, the sides of the decorative flange tapering equally on either side of the decorative edge toward a straight portion, a longitudinal rib adjacent said straight portion projecting on one side of said strip, a straight portion below said rib, and a second longitudinally extending rein- 120

forcing rib projecting on the other side of said strip.

10. A floor separating strip having a ribbon-like nature, straight portions extending in line in approximately the same plane longitudinally through said strip, protruding longitudinal-anchoring portions formed in said strip and interposed in said straight portions, a series of openings through said strip adapted to receive anchoring pins, and a waved decorative flange extending along one side of said strip.

11. A ribbon-like separating strip including, a portion waved to form a decorative edge, and a body portion disposed adjacent the decorative portion of said strip being centrally aligned therewith in a manner to project from either side thereof to form longitudinally extending anchoring means therein for the purpose set forth.

ANDREW STRAND.
